LAMP MOUNTING FOR CERTAIN OPTICAL INSTRUMENTS

Filed March 15, 1920

REINHOLD H. WAPPLER
INVENTOR
BY Walton Harrison,
ATTORNEY

UNITED STATES PATENT OFFICE.

REINHOLD H. WAPPLER, OF YONKERS, NEW YORK, ASSIGNOR TO AMERICAN CYSTOSCOPE MAKERS, INC., A CORPORATION OF NEW YORK.

LAMP MOUNTING FOR CERTAIN OPTICAL INSTRUMENTS.

Application filed March 15, 1920. Serial No. 365,834.

To all whom it may concern:

Be it known that I, REINHOLD H. WAPPLER, a citizen of the United States, residing at Yonkers, in the county of Westchester and State of New York, have invented certain new and useful Improvements in Lamp Mountings for Certain Optical Instruments, of which the following is a full, clear, and concise description.

10 My invention relates to lamp mountings for certain optical instruments, my general purpose being to enable the operator to quickly and easily lock the lamp in adjusted position relatively to other parts.

15 More particularly stated, my invention deals with a miniature incandescent lamp bulb having a hood and provided with a threaded supporting stem to be screwed into a lamp socket carried by a tubular sheath 20 or optical barrel through which the operator gazes by aid of light from the lamp; and my improvement contemplates means whereby the operator, in turning the lamp bulb, incidental to screwing the stem thereof into 25 the lamp socket, can always leave the lamp socket in such position that the lamp window occupies a predetermined normal position relatively to other parts.

Reference is made to the accompanying 30 drawing forming a part of this specification, and in which like reference characters indicate like parts throughout the several figures.

Figure 1 is a side view, partly in elevation 35 and partly in section, showing one form of my invention as applied to a cystoscope.

Figure 2 is a plan view of the device shown in Figure 1.

Figure 3 is an enlarged fragmentary section, 40 corresponding to a portion of Figure 1.

Figure 4 is a vertical longitudinal section through a certain form of endoscope, equipped with a form of my invention differing from that appearing in Figures 1 45 and 2.

Figure 5 is a section on the line 5—5 of Figure 4, looking in the direction indicated by the arrows.

The optical barrel of a cystoscope is shown 50 at 4, and is made of metal. The eye piece appears at 5, a lens at 6, and a speculum at 7. This speculum is of the type known as a three-quarters sphere. It would be spherical

except for the fact that about one-quarter of it is cut away. A wedge-shaped base 8, 55 housed within the barrel 4, is used in supporting the speculum.

The optical barrel 4 is provided with an upturned cylindrical end portion 9, threaded internally at 10 and serving as a lamp socket. 60 Fitted into this socket is a bushing 11 of insulating material, carrying a contact member 12 of metal. This contact member is provided with a spring portion 12a. Connected with the contact member 12 is an insulated wire 13, leading to a binding post 14, carried by the barrel 4 and insulated therefrom. Another binding post 15 is mounted upon the barrel 4 and is in metallic contact therewith. 65

A miniature incandescent lamp bulb 16 carries a lamp hood 17, made of metal and provided with a window 18. The lamp bulb is provided with a threaded sleeve 19, carrying a cylindrical member 19a of insulating 75 material, of the kind commonly used with lamp bulbs of this type, and is further provided with the usual centrally-disposed contact button 20. The threaded supporting stem 19 and the contact button 20 are connected with the lamp filament, shown at 21. 80

The parts are so proportioned and arranged that the contact button 20, carried by the lamp bulb, can be brought into engagement with the contact member 12 by 85 screwing the stem 19 into the socket 9.

A locking ring 22 is revolvably mounted upon the threaded stem 19, and for this purpose is threaded internally. This locking ring serves generally the purpose of a jam 90 nut. When forced tightly against the adjacent end portion 9 of the barrel 4, it locks the lamp stem 19 rigidly in relation to the barrel. In doing this, it virtually locks the lamp bulb, and the hood 17 carried thereby, 95 rigid relatively to the barrel. When this is done, there is usually a slight space 23 between the locking ring 22 and the adjacent end portion of the lamp hood.

The contact button 20 should always be 100 in actual engagement with the contact member 12 before the locking ring 22 is forced against the portion 9 of the barrel.

The purpose of the locking ring 23 is to 105 so secure the stem 10 and all parts carried thereby as to leave the window 18 facing in

exactly the same radial direction as the exposed portion of the speculum 7.

With the device in the condition just described, the lamp circuit may be traced as follows: Binding post 14, wire 13, contact member 12, contact button 20, lamp filament 21, stem 19, barrel 4, binding post 15 to source of electricity (not shown), and thence back to binding post 14. This circuit energizes the lamp.

Except for the use of the locking ring 23, in the relation above described, the lamp window might face in almost any radial direction when the lamp stem reaches the limit of its travel in the socket.

Since incandescent bulbs of this type are renewed quite often, and since as a rule such lamp bulbs are not exactly alike, it may readily be seen that special provision is necessary in order to enable the lamp window to be brought into exact registry with the exposed portion of the speculum 7, as above described.

In Figures 4 and 5 I show another form of my device, applied in this instance to an endoscope.

The barrel of the endoscope appears at 24 and the eye piece at 25. Mounted within the barrel is a lens 26, supported in position by a mounting 27. The eye piece 25 carries a supporting pin 28, and mounted upon the latter is a plate 29. The upper end of this plate serves as a lamp socket and is suitably formed for the purpose.

An incandescent lamp bulb is shown at 30, and is provided with a threaded stem 31. A locking ring 32 is revolvably fitted upon this stem, and serves to lock the stem 31 rigidly in relation to the plate 29.

The incandescent lamp bulb is provided with a filament 33, having the form of a flat loop, as shown. When the device is in active use, the plane of the filament should be vertical. This is on account of the optical relations of the filament to the lens 26, and to the position of this lens relatively to the barrel 24. That is to say, the distribution of the light from the filament should always be such as to enable the operator to look through the

barrel 24 by glancing over the top of the plate 29, and experience shows that with the operator thus looking through the barrel the light is distributed to the best advantage when the general plane of the filament is strictly diametrical relatively to the barrel, and therefore vertical as the device is normally used. Another way of stating practically the same thing is, that the lens 26 distributes the light to better advantage if the filament occupies a vertical plane crossing the optical center of the lens.

The lamp bulb 30 is first adjusted by turning it until the plane of the filament occupies the position just described, and then the locking ring 32 is jammed against the

plate 29, so as to lock the bulb rigidly in position.

Thus in a general way the function of the locking ring 32 is closely analogous to that of the locking ring 22 above described.

I do not limit myself to the precise mechanism shown, as variations may be made therefrom without departing from my invention, the scope of which is commensurate with my claims.

Having thus described my invention, what I claim as new and desire to secure by Letters Patent is as follows:

1. In a device of the character described the combination of an optical barrel, a lamp socket carried by said optical barrel, an incandescent lamp bulb provided with a stem fitting into said lamp socket in order to support said incandescent lamp bulb thereupon, so that said lamp bulb may be turned relatively to said socket, and means controllable at the will of the operator for securing said stem in different radial positions relatively to said socket.

2. In a device of the character described the combination of an optical barrel, a lamp socket carried by said optical barrel, an incandescent lamp bulb provided with a stem fitting loosely into said lamp socket in order to support said incandescent lamp bulb, thereupon so that said lamp bulb may be turned relatively to said socket, and a clamping ring mounted upon said stem for the purpose of locking said stem relatively to said socket.

3. The combination of a lamp socket provided with a thread, an incandescent lamp bulb provided with a thread for engaging the thread of said lamp socket in order to support said incandescent lamp bulb thereupon so that said bulb may be turned relatively to said socket, and a clamping ring mounted upon said stem and revoluble relatively thereto in order to jam against said socket and thus to hold said lamp bulb in different radial positions relatively to said socket.

4. The combination of an optical barrel, an incandescent lamp bulb supported by said barrel and adjustable relatively thereto for the purpose of enabling the operator to see through said optical barrel, and means controllable at the will of the operator for clamping said lamp bulb in any predetermined one of an infinite number of positions relatively to said barrel.

5. The combination of an optical barrel, a speculum carried thereby and facing radially therefrom, a hood mounted upon said optical barrel and provided with a window, said hood being revoluble relatively to said barrel in order to turn said window relatively to said speculum, a lamp mounted within said hood and adapted to shed light through said window, and means control-

lable at the will of the operator for clamping said hood in a predetermined position relatively to said barrel.

6. The combination of an optical barrel, provided with a threaded portion, a speculum carried by said barrel and facing radially therefrom, an incandescent lamp bulb provided with a threaded portion engaging said threaded portion of said barrel, a 10 clamping ring carried by said threaded portion of said lamp and fitted so that at the will of the operator said clamping ring may be jammed against said barrel, so as to secure said incandescent lamp bulb in a predetermined position relative to said barrel, and a hood mounted upon said incandescent lamp bulb and provided with a window which faces radially therefrom.

7. The combination of an optical barrel

provided with a threaded portion, a speculum carried by said barrel and facing radially therefrom, a lamp provided with a threaded stem for engaging said threaded portion of said barrel, so that said lamp may be turned relatively to said barrel, a 15 locking ring revolubly mounted upon said stem and adapted to be jammed against said barrel in order to lock said lamp in a predetermined position relative to said barrel, and a shielding member carried by said 20 lamp and adjustable therewith relatively to said barrel, said shielding member having a window so positioned that the adjustment of said lamp brings said window into a predetermined position relative to said speculum.

REINHOLD H. WAPPLER.
